UNITED STATES PATENT OFFICE.

OLIVER H. HOVDA, OF BILLINGS, MONTANA.

NAIL-SORTING DEVICE.

Application filed March 1, 1926. Serial No. 91,555.

The present invention relates to improvements in nail sorting devices and consists in certain improvements over the similarly entitled inventions shown and described in 5 my co-pending applications Serial No. 742,657, filed October 9, 1924, and the division thereof, Serial No. 79,856, filed January 7, 1926.

It is an object of the present invention to 10 improve the construction of the trays or sorting sieves as described in the above referred to applications to the end that a more expeditious and faithful sorting of the nails may be secured.

15 It is another object of the invention to provide a device which will be compact and which by reason of the incorporation of moving sorting parts therein, will greatly increase the capacity of present devices.

20 With the foregoing and other objects in view, the invention will be more fully described hereinafter, and will be more particularly pointed out in the claims appended hereto.

25 In the drawings, wherein like symbols refer to like or corresponding parts throughout the several views,

Figure 1 is a vertical section taken centrally through an improved nail sorting device constructed according to the present invention;

Figure 2 is a top plan view thereof;

Figure 3 is a fragmentary vertical cross-section through the same taken at right angles to Figure 1.

Referring first to Figures 1, 2 and 3, 8 designates an appropriate framework or base upon which vertical longitudinal spaced walls 9 and 10 are erected. These walls 40 are mounted in pairs and are spaced from each other and also from adjacent pairs of walls. The space between the walls 9 and 10 is greater than the space between the pairs of walls. The space between the walls 9 and 10 is covered at the upper portion by covering strips 11 of substantially triangular form having upper pressed portions and divergently sloping walls therefrom which direct the nails thrown upon

50 the device toward the slots 12 and into the spaces between the pairs of walls 9 and 10. In these spaces are arranged belts in any suitable number, the belts being superposed, one above the other. In the instance shown, three supersposed sets of belts are 55 shown and these belts extend about drive

pulleys 13, 14 and 15, mounted upon the drive shafts 16. These drive shafts are erected in the space between the walls 9 and 10 and extend below the base 8, where they 60 are provided with the gear wheel 17 and mesh with power gear wheels 18 driven from a suitable source of power. The various belts are indicated at 19, 20 and 21, and they are preferably of different lengths as 65 shown in Figure 1. Here the lowermost belt is the shortest belt and the belts are graduated in length from the lowermost to the uppermost belt, which latter is the longest. The graduated ends of the belts extend 70 around the pulleys 22, 23 and 24 mounted upon the shafts 25, 26 and 27, respectively, and such graduated ends of the belts are arranged to deliver the nails to separate chutes 28, 29 and 30. These chutes may 75 carry the nails to appropriate bins or receptacles.

The walls 9 and 10 are provided with ledges 31, 32 and 33 extending into the sorting space for catching the adjoining runs of 80 the belts and supporting the same during the time these belts carry the nails. The belts are driven in the direction of the arrows indicated in Figure 2 and the upper edges of each of the belts are enlarged and formed 85 with the inwardly projecting lips 34 and with the upwardly sloping surfaces above the lips. These lips project inwardly with reference to the slot through which the nails drop onto the belts. It will be seen from 90 Figure 3 that the lowermost belts 19 are disposed closest together as to their runs in the nail slot. The next higher belts 20 are spaced slightly wider apart to receive nail heads of slightly greater diameter and to 95 prevent them from falling through to the lowermost belts. The heads of the nails are caught upon the upper beaded or headed edges of the belts and the heads will lie upon the upper sloping surface of these beaded edges, while the shanks of the nails will drop down between the belts. The nails will be 100 carried along by the belts toward the chutes 28, 29 or 30.

The uppermost belts 21 are located wider 105 apart in the nail slots in order to receive only the largest nails fed into the device.

Of course, it will be understood that two or more belts may be used and that the belts may be mounted and driven in any appropriate manner. The device shown is appropriate for sorting by head nails of three 110

different sizes,—for instance, three penny common, three penny fine, and three penny extra fine. The belts will carry the nails along and effectively prevent clogging of the device.

5 The beaded edge or projection at the tops of the belts may not be necessary in handling small sizes of nails, say up to five penny.

10 It is obvious that various changes and modifications may be made in the details of construction and design of the above specifically described embodiment of this invention without departing from the spirit thereof, such changes and modifications being restricted only by the scope of the following 15 claims.

Having thus described my invention, what I claim and desire to secure by Letters Patent of the United States is:—

20 1. A nail sorting device comprising a slot-

ted framework having angle strips for diverting the nails to the slots, and a series of superposed belts having their adjacent runs disposed in the slots, the adjacent runs of 25 the belts being spaced apart in graduated scale, said belts having upper beaded edges to receive the heads of the nails.

2. A nail sorting device comprising a base, spaced walls erected thereon with slots between the walls, said walls having ledges projecting into the slots, shafts erected between the walls, means for driving certain of the shafts, pulleys on the shafts, belts extending about the pulleys with adjacent 30 runs of the belts disposed in the slots and supported upon said ledges, the upper edges of said belts being formed into enlarged beads with inwardly projecting portions and with sloping upper edges.

OLIVER H. HOVDA.
